UNITED STATES PATENT OFFICE.

WILHELM THEODOR UNGE, OF STOCKHOLM, SWEDEN.

SELF-PROPELLED PROJECTILE.

961,179.

Specification of Letters Patent. Patented June 14, 1910.

Application filed September 19, 1908. Serial No. 453,865.

To all whom it may concern:

Be it known that I, WILHELM THEODOR UNGE, a subject of the King of Sweden, and resident of Stockholm, in the Kingdom of Sweden, have invented certain new and useful Improvements in Self-Propelling Projectiles, of which the following is a specification, reference being had therein to the accompanying drawing.

10 Self-propelling projectiles, as flying torpedoes, rockets and the like are commonly started and kept in motion by the reaction of gas expanding in the projectile and escaping through an opening in the rear end 15 of the same. The said expanding gas is generated by the burning of a motive composition provided in the projectile. In order that the said composition when ignited may generate in a short time the necessary 20 quantity of expanding gas, it must have a great combustion surface, which is furnished by a cylindrical or conical channel being provided in the center line of the motive composition to a certain depth from 25 the exit opening, so that the projectile contains partly a pierced composition and partly a solid composition. Consequently, the torpedo or rocket is put in motion by fire being introduced into the said channel 30 through the exit opening or the muzzle, the whole surface of the central channel and the bottom of the solid part being thereby ignited and generating the quantity of expanding gas necessary for propelling the 35 projectile.

The object of this invention is to introduce the fire, without the risk of explosion, from a part of the projectile, which is more accessible than the part hitherto used. The 40 fire has been introduced previously through the exit opening in the rear end of the projectile, or through breech-ignition, at which opening there are generally, in such projectiles as rockets or flying torpedoes 45 used for the throwing of life-lines at shipwrecks, parts preventing the introducing of the fire or the rapid mounting of igniting means or the changing of defective igniting means.

50 The invention consists in the front wall opposite the exit opening of the projectile, being provided with a central opening, which cannot be widened by the escaping gas of high temperature and communicates 55 through a channel, provided in the solid part of the composition, with the front end

of the said channel in the motive composition; in order that it may be possible to introduce through the head or front wall of the projectile a fire jet into the central 60 channel and ignite the surface of the same, so that the projectile in this manner is put in motion by front-ignition and not by the introduction of the fire through the muzzle or by breech-ignition as in projectiles hitherto used. Owing to the said arrangement the expanding gas will escape from the projectile through two straight opposite openings viz: the muzzle in the rear end of the projectile and the igniting opening in the 70 front end of the same. By rendering the igniting opening narrower than the muzzle, the movement direction forward is however, not changed but the propelling force is reduced. In order to reduce the said loss of 75 force to a minimum, the igniting opening is made very narrow and only so wide, that a fire jet can pass from outside through the same and ignite the motive composition. Such a fire jet is effected by a small charge 80 of gun-powder for instance mounted outside the igniting opening and ignited by means of fuse or in any other suitable manner. In order to fully obviate the said loss of force the charge of powder last mentioned 85 may be inclosed in a gas tight chamber. In such case the ignition is effected preferably by an electric spark. The gas generated in the projectile, which tends to escape through the igniting opening, is then prevented from escaping, no motive force being, consequently, lost. Consequently, in 90 the arrangement, last mentioned, the width of the igniting opening is independent of the cross sectional area of the exit opening and may for that reason be of any desired size without influencing the movement of the projectile through the air.

In the accompanying drawing, Figure 1 is a longitudinal section of a rocket provided 100 with igniting means in accordance with this invention. Fig. 2 is a longitudinal section of for instance Unge's flying torpedo, to which the invention is applied.

1 is the ordinary tube fixed to the stick 2. 105
3 is the muzzle, 4 the conical central channel or combustion surface and 5 the solid part of the motive composition.

6 is a disk of a material difficult of combustion as for instance metal, porcelain or 110 the like and provided with a hollow projection 7, extending forward and containing a

2 small charge of gun-powder 8. In the disk 6 an opening 9 is provided which communicates with the channel 4 through a channel 10 in the front part 5 of the composition. 5 The said charge of gun-powder can be ignited by means of fuse 11 fixed in the projection 7. As the small charge 8 of gun-powder is ignited by the ignited fuse 11, a jet of fire is forced through the opening 9 and 10 channel 10 into the channel 4 and ignites the motive composition of the rocket. The generated gas begins immediately to pass through the muzzle 3 as well as through the igniting opening 9. Owing to the fact that 15 the area of the former is greater than that of the opening 9 the rocket is, notwithstanding, forced forward.

In the flying torpedo, shown in Fig. 2, 12 is the steel shell of the torpedo, 13 the turbine, through which the gas escapes, 14 the forward wall of the torpedo, 15 an igniting opening in the said forward wall, leading from a chamber 17 provided with a cover 16 in screw threaded engagement with the 25 wall of the chamber, said chamber containing the igniting charge in the shape of an electrical igniter 18 of suitable construction inserted in the chamber. If the said igniter is arranged to be operated centrally, 30 one of its terminals is in contact with a conductor 19 mounted in the cover 16 and insulated from the same, while the other terminal (the shell of the igniter) is in contact with the metallic parts of the torpedo. A 35 conical part 20 is mounted between the cover 16 and the shell 12 for steadyng the point of the torpedo. 10 is the channel connecting the opening 15 and the central channel 4 in the motive composition of the torpedo.

40 As an electric current is led into the igniter 18 through the conductor 19, the charge in the igniter is ignited and a jet of fire is forced through the igniting opening 15 and ignites the motive composition. 45 The gas escapes through the turbine 13 and propels the torpedo, during which operation the cover 16 and the igniter 18 prevent the gas from escaping forward through the igniting opening. If the connecting channel 50 10 is to be dispensed with, the central channel 4 may be extended to the opening 15,

as indicated by the dotted lines 21. If the igniting operation is to be effected by means of fuse a charge of gun-powder is substituted for the igniter 18 in the chamber 17, 55 a fuse being mounted in the cover in the manner as shown in Fig. 1.

Having now described my invention, what I claim as new and desire to secure by Letters Patent is:

1. A self propelling projectile having a casing, a combustible composition contained therein and arranged to generate a rearwardly directed propelling fluid, and provided with a longitudinal channel forming a combustion surface and extended toward the rear end of the projectile, and an ignition opening at the forward part of the projectile and communicating with said channel. 65

2. A self propelling projectile having a casing, a combustible composition contained therein and arranged to generate a rearwardly directed propelling fluid, and provided with a longitudinal channel forming a combustion surface and extended toward the rear end of the projectile, a material difficult of combustion arranged at the forward 75 part of the projectile and having a chamber provided with a charge, means for igniting the charge in said chamber, and a passage 80 affording communication from said chamber to said longitudinally extended channel.

3. A self propelling projectile having a casing, a combustible composition contained therein and arranged to generate a rearwardly directed propelling fluid, and provided with a longitudinal channel forming a combustion surface and extended toward the rear end of the projectile, a material difficult of combustion arranged at the forward 85 part of the projectile and provided with a chamber, a passage affording communication from said chamber to said longitudinal channel, and an igniter arranged in said chamber. 90

In witness whereof, I have hereunto signed my name in the presence of two subscribing witnesses.

WILHELM THEODOR UNGE.
